UNITED STATES PATENT OFFICE.

ELBERT L. COUCH, OF FARMINGTON, AND GEORGE H. CONNERS, OF HARTFORD, CONNECTICUT.

CIGAR.

1,849,147.

Specification of Letters Patent. Patented Aug. 10, 1920.

Application filed June 9, 1920. Serial No. 387,551.

To all whom it may concern:

Be it known that we, ELBERT L. COUCH and GEORGE H. CONNERS, citizens of the United States, residing at Farmington and

5 Hartford, respectively, in the county of Hartford and State of Connecticut, have invented certain new and useful Improvements in Cigars, of which the following is a specification.

10 This invention relates to cigars. We provide a device of ignitable character associated with the cigar by which it may be lighted, this ignitable device forming in effect a practically permanent part of the 15 cigar although it is true that it may be in part or *in toto* removed when the cigar is to be lighted. The label and lighter element is desirably of such a character that upon the lighting of the cigar this element is destroyed. 20 This element as will be inferred carries for instance, identifications of the cigar after the fashion of the customary bands, which is destroyed or at least rendered useless the instant the cigar is lighted, 25 this being an important features when it is realized that the present and well-known cigar bands intended for high-grade cigars are frequently by unscrupulous dealers, put on inferior ones. We use the term cigars 30 somewhat as a matter of convenience. It is conceivable of course that the invention may be associated with things other than cigars of which a cigarette is an example. In like fashion the label itself presents an 35 article of manufacture, which is capable of production independently of the cigar.

In the drawings accompanying and forming part of the present specification, we have shown two of the many forms of embodiment of the invention which to enable those skilled in the art to practice the same will be set forth fully in the following description. Obviously we are not restricted to this disclosure. We may depart therefrom 45 in several respects within the scope of the invention defined by the claims following said description.

Referring to said drawings:

Figure 1 is a side elevation of a cigar 50 furnished with combination label and lighter involving the invention.

Fig. 2 is a view at right angles of the tuck end of the cigar.

Fig. 3 is an elevation as seen from the right in Fig. 1.

55

Fig. 4 is a flat view of the label.

Fig. 5 is an elevation of a modification.

Like characters refer to like parts throughout the several views.

The cigar shown is denoted by 2. Associated with it is a combined label and lighter which will be hereinafter described, and which is desirably associated with the tuck end of the cigar as distinguished from the head end. This tuck end (on the right in 65 Figs. 1 and 2) has a longitudinal recess or aperture as 3 constituting a convenient seat or a holder, for the combined label and lighter. The combined label and lighter shown in Figs. 1, 2 and 3 as operatively associated with the cigar 2 and in practically blank condition in Fig. 4, comprises a body as 4 usually of some inflammable stock such for instance as paper, although some other substance could be employed as well. This 70 body desirably coated by some inflammable substance such as paraffin, which we prefer cover its entire surface. The body 4 has a transverse fold line 5 practically at its center so that the body can be folded on said 75 line to present two branches 6 of duplicate character which can be brought closely together to produce a two-part shank which will be inserted in the recess or aperture 3 as clearly shown in Fig. 1, this two-part 80 shank bottoming or practically bottoming in the recess or aperture 3. The body 4 has at its outer end the widened lugs or ears 7 which as shown are duplicates of each other and these lugs or ears are bent at practically 85 right angles to the branches 6 so as to extend outwardly therefrom and thus bring them into transverse line with each other. The inner surfaces of these ears or lugs when the label and lighter is in assembled 90 relation with the cigar, are contiguous to the flat outer tuck end of the cigar. The ears or lugs 7 on their outer surfaces bear identification data of some kind, usually corresponding with that found on the ordinary 95 band. The upper lug or ear 7 in Fig. 4 may for instance bear the name of the cigar and

80

the lower one the place at which the cigar is manufactured or there might be any other data. The characters or symbols 8 on these lugs or ears 7 are preferably raised and one set is of some inflammable substance the other being a complemental substance, the background of the lugs or ears being sanded or having some other abrasive material. The inflammable substance 8 on one lug 10 will be caused to ignite when brought against and rubbed back and forth against the substance on the other lug or ear. This result causes the combined label and lighter to flame and this in turn will be communicated 15 to the cigar to light it so that the user having removed the head of the cigar can then light it. There is an advantage in having the body of the label and lighter of wedge formation in that this is introduced, for 20 instance into a dry cheap cigar, after having been intended for one of a better quality, the sides of the wedge body will break the cheaper cigar and thus render it unfit for use.

25 In Fig. 5 is a tube 10 which is to be inserted in a seat in the tuck end of the cigar, this tube having at its outer end the head 11. The tube 10 and its flange or head 11 are of paper or some other inflammable material and may as before, be coated with paraffin or something of an equivalent nature, to promote combustion. The head or flange which will be adjacent the tuck end of the cigar, may have printed on its outer 35 surface data such as we have described. The tube 10 is adapted to receive a pin 12 of metal, wood or other suitable material, and which is provided with a scratching surface to ignite the paper tube 10 as the pin 12 40 is pulled from it.

In both forms of our invention and in others that we have in mind, the combination label and lighter presents all the attributes of a protective element; that is to 45 say it protects the brand of the user. The

article also is a novelty and in addition to this advertises the brand and the maker of the cigar.

What we claim is:

1. A cigar provided with a combination 50 lighting and advertising member, the advertising means being adapted to light said member.

2. A cigar provided with a combination 55 lighting and advertising member at the tuck end thereof, the advertising means being adapted to light said member.

3. A cigar provided with a combination 60 lighting and advertising member at the tuck end thereof, the advertising member being movable to cause the advertising matter to ignite the member and therefore the cigar.

4. A cigar provided with a combination 65 lighting and advertising member having a wedge fit in the tuck end thereof.

5. A cigar provided with a member fitted 70 in the tuck end thereof and having advertising means to ignite itself and thus the cigar.

6. An igniting device for a cigar comprising 75 a wedge like body having two branches to fit flatwise against each other and having ears carrying advertising matter which functions also to ignite the ears.

7. An igniting device for a cigar comprising 80 a wedge like body having two branches to fit flatwise against each other, and having ears carrying advertising matter which functions also to ignite the ears, said device being insertible in the tuck end of a cigar with the ears folded back against the cigar end.

In testimony whereof we affix our signatures.

ELBERT L. COUCH.
GEORGE H. CONNERS.

In presence of—

HEATH SUTHERLAND,
ELIZABETH A. BANNING.
